(57) **CLAIM**

The ornamental design for a combination goalkeeper game piece and bottle opener as shown and described.

DESCRIPTION

FIG. 1 is a top back perspective view of a combination goalkeeper game piece and bottle opener.

FIG. 2 is a back view of the combination goalkeeper game piece and bottle opener of FIG. 1.

FIG. 3 is a front view of the combination goalkeeper game piece and bottle opener of FIG. 1.

FIG. 4 is a left-side view of the combination goalkeeper game piece and bottle opener of FIG. 1 (the right-side view is a mirror image of the left-side view and therefore is not shown).

FIG. 5 is a top view of the combination goalkeeper game piece and bottle opener of FIG. 1; and,

FIG. 6 is a bottom view of the combination goalkeeper game piece and bottle opener of FIG. 1.

The broken lines in the drawings depict portions of the article that form no part of the claimed design.

1 Claim, 6 Drawing Sheets
